CLAIM

The ornamental design for a media plug adapter as shown and described.

DESCRIPTION

FIG. 1 is a top view of a media plug adapter.

FIG. 2 is bottom view thereof.

FIG. 3 is a first side view thereof.

FIG. 4 is a second side view thereof.

FIG. 5 is a first end view thereof.

FIG. 6 is a second end view thereof.

FIG. 7 is a perspective view thereof; and,

FIG. 8 is a second perspective view thereof.

The features shown in broken lines do not form part of the claimed design.
